CLAIM

The ornamental design for a sandal covered with indoor/outdoor carpet, as shown and described.

DESCRIPTION

FIG. 1 is a top plan view of a sandal covered with indoor/outdoor carpet showing my new design;

FIG. 2 is a bottom plan view thereof;

FIG. 3 is a side elevational view thereof;

FIG. 4 is a rear elevational view thereof; and,

FIG. 5 is a front elevational view thereof.

The surfaces of the other side, not shown, form no part the claimed design.
